[57] CLAIM

The ornamental design for a bush cutter, as shown and described.

DESCRIPTION

FIG. 1 is a front view of a bush cutter embodying our design;

FIG. 2 is a back view thereof;

FIG. 3 is a top plan view thereof;

FIG. 4 is a bottom plan view thereof;

FIG. 5 is an enlarged left side elevational view thereof;

FIG. 6 is an enlarged right side elevational view thereof;

FIG. 7 is an enlarged front elevational view thereof;

FIG. 8 is an enlarged back elevational view thereof;

FIG. 9 is an enlarged top plan view thereof;

FIG. 10 is an enlarged bottom plan view thereof;

FIG. 11 is a front elevation view of a second embodiment of a bush cutter according to our design;

FIG. 12 is a top plan view thereof;

FIG. 13 is a left side elevational view thereof;

FIG. 14 is a right side elevational view;

FIG. 15 is a front elevational view of a third embodiment of a bush cutter according to our design;

FIG. 16 is a top plan view thereof;

FIG. 17 is an enlarged left side elevational view thereof; and,

FIG. 18 is an enlarged right side elevational view thereof.

The shaft is shown broken away in FIGS. 7-10 for ease of illustration. The undisclosed rear views of the second and third embodiments are identical to that shown in FIG. 8.
